UNITED STATES PATENT OFFICE.

HORACE G. INGRAM, OF JUNIATA, PENNSYLVANIA, ASSIGNOR OF ONE-HALF TO
SAMUEL GOLDBERG, OF ALTOONA, PENNSYLVANIA.

SCREW-DRIVER.

1,039,751.

Specification of Letters Patent.

Patented Oct. 1, 1912.

Application filed September 28, 1911. Serial No. 651,804.

To all whom it may concern:

Be it known that I, HORACE G. INGRAM, a citizen of the United States, residing at Juniata, in the county of Blair and State 5 of Pennsylvania, have invented new and useful Improvements in Screw-Drivers, of which the following is a specification.

The object of my invention is to provide a screw driver with an attachment for holding the screw while it is being started in 10 the wood or metal.

A further object of my invention is to accomplish this end by means of a device which can be operated with one hand and 15 while in positions where it is difficult to reach the right spot.

With this and other objects in view my invention consists of a combination and arrangement of parts shown in the accompanying drawing, in which—

Figure 1 is a view of the screw driver complete. Fig. 2 is a section through the center of Fig. 1. Fig. 3 is a similar section at a right angle to Fig. 2 showing one of 25 the gripping jaws in open position to grasp the screw. Fig. 4 is a section on line "4 4" Fig. 2. Fig. 5 is a section on line "5 5" Fig. 2. Fig. 6 shows the lower end of the screw driver. Fig. 7 is a side view of the 30 lower end of the blade. Fig. 8 is a side view of one of the gripping jaws.

Similar letters and figures refer to similar parts throughout the drawing.

My invention consists of a blade "1" 35 which is fastened in a handle "6" similar to the ordinary screw driver. Alongside of the blade of the screw driver "1" and on opposite sides thereof are two spring jaws "2 2", substantially of the shape shown, extending through the handle and projecting 40 a short distance beyond at its rear end. These spring jaws are intended to automatically spread when the tube "3", which surrounds them, is moved backward toward the handle by means of a projection "4", which compresses a spring "5." When the projection "4" is released the spring "5" forces 45 the sleeve "3" forward and closes the jaws either upon the screw or upon the lower portion of the blade, as shown at "11'." The jaws "2 2" have a slightly curved depression "14" which centers the screw and helps hold it securely in place. At the rear end 50 of the stems which are fastened to the jaws "2 2" and which pass entirely through the

handle, is secured a knob "7." A coil spring "8" surrounds this rear end and acts so as to hold the jaws in the position shown in Figs. 1 and 2. This spring "8" is slightly weaker than the spring "5" so that the 60 spring "5" will overcome the action of spring "8." Depressions "9" and "10" may be formed in the rear and front ends of the handle for seating the springs "8" and "5" respectively. The sleeve "3" is 65 held in place by means of a slot "11" and pin "12", which allows free movement longitudinally but prevents rotation of the sleeve. As stated before, the rear end of the blade is fastened rigidly in the handle 70 but on either side there is sufficient space allowed so that the jaws may move freely in a longitudinal direction. This blade may either be flat or round, in which latter case the jaws are made to conform with the 75 rounded blade.

From this description it will be seen that the operation of the device is as follows:— When a screw is to be started the handle is 80 grasped with the fingers and the knob "7" rests in the palm of the hand. The portion "4" is then grasped by the fore-finger and thumb and drawn backward. The jaws "2 2" automatically spring outward leaving the notches "11' 11'", and by further pressure upon the knob "7" the jaws are pushed forward through the tube until they are in the position shown in Fig. 3. If the projection "4" is then released and pressure 85 is exerted on the handle, the blade of the screw driver will engage the slot in the head of the screw and it can be turned into position without any difficulty. When the screw is started the jaws can be returned to their original position by merely pulling back the 90 sleeve "3" and the jaws will spring out automatically disengaging themselves from the screw head and they can readily be returned to the position shown in Fig. 1, as the spring "8" has been compressed and 95 will materially assist if not entirely return them to their proper position.

From this it will be seen that the device 100 can readily be handled with one hand and can be used in places where the operator must use his other hand to hold on.

I do not desire to limit myself to the absolute details of construction as shown, but merely to the structure in its broad sense of 105 operation.

What I claim is—

1. In a screw driver the combination of a handle, a blade fastened rigidly in said handle, an opening completely through the handle, spring jaws passing through said opening, a movable sleeve surrounding said jaws and blade, and means for holding the jaws and blade in the relation desired by the operator.
- 10 2. In a screw driver the combination of a handle, a blade fastened rigidly in the handle, notches near the lower end of said

blade, an opening completely through the handle, spring jaws passing through said opening, a movable sleeve surrounding said 15 jaws and blade, coiled springs at the upper and lower ends of said handle and surrounding said jaws so that the jaws will operate to hold the screw to be inserted or engage the notches in the blade.

HORACE G. INGRAM.
